UNITED STATES PATENT OFFICE

EMILE BERLINER, OF WASHINGTON, DISTRICT OF COLUMBIA

WALL

Application filed February 5, 1929. Serial No. 337,653.

This invention relates to walls, and more specifically to a wall formed with a plurality of hollow cells which are defined by cell molds or members attached to an unfinished wall surface and subsequently covered with a coat of cement thereby to impart to the finished wall surface the vibratory characteristics of diaphragms, possessing marked qualities of resonance and sound reflection, and at the same time preventing reverberation.

The invention is particularly applicable to masonry walls, such as those of auditoriums, theaters, concert halls, churches and the like where good acoustics are most desirable. In masonry walls as at present constructed the solidity of the structure promotes reverberation, and such walls are found to be almost entirely lacking in that resonant property so essential for a good acoustic effect.

My prior U. S. Patent No. 1,628,351, discloses cell members of fine mesh wire screen material which are affixed to the unfinished surface of a wall and then covered with a layer of cement. I have found, however, that to impart the necessary quality of resonance to a wall the cell members should be fairly rigid and of a material which will not be easily and permanently deformed by the plasterer when he presses the acoustic cement over the wire meshes. Such a deformed cell reduces the vibrations of the cement diaphragms formed.

A cell of coarse mesh wire, while it resists deformation because of its heavier and more sturdy structure, permitted the cement with which the cells were afterward covered to penetrate and fill or partially fill the cellular space and thus spoil the structure by which the acoustic diaphragm effect was to be obtained. In the practice of the invention disclosed in my aforesaid patent cells of fine mesh wire fabric were used since they obviated this disadvantage, but the fine mesh fabric, itself, possesses the disadvantage of being structurally non-elastic and consequently easily deformed. The outer coat of cement, however, being vibratory because of the cellular spaces beneath its surface tended to pull away from its interlocking engagement

with the wire cells, thus causing the formation of numerous small cracks in the wall surface.

The present invention is an improvement over that disclosed in my prior patent and overcomes the defects noted. I have found that a cell member of coarse wire screen material possesses the desired rigidity to withstand the stresses to which it is subjected when being covered, without permanent deformation, and is of sufficiently elastic character to permit vibration of the cement wall surface without tendency to separate from it and thus form cracks in the wall surface.

To prevent penetration of plaster through the interstices of the coarse mesh cell, a sheet of paper, fiber, cloth or other suitable material is glued, cemented or affixed in any other approved manner to one surface of the wire fabric, which is subsequently stamped into diaphragm shape with an inturned annular flange. The skeleton wire frame of the cell being outermost presents a rough surface to which the cement coat will readily adhere, but because of the lining no cement can penetrate into the cellular space which it defines.

It is accordingly an object of my invention to provide a structure which is permanent and non-inflammable and which, at the same time, possesses the desired acoustic properties of wood walls, being of vibratory character and a good reflector and diffuser of sound.

A further object is to provide a cellular wall structure so formed that a resonant quality is imparted to the wall surface.

A still further object is to provide, on an unfinished wall surface a plurality of cell members of sufficient rigidity and elasticity to resist permanent deformation while being made, such cell members being lined with a material to prevent penetration of cement into the spaces defined by them and a surface coating of cement applied to said cell members and the spaces between them to interlock therewith so that the vibratory characteristic of a diaphragm is imparted to the wall surface.

Other and further objects will be apparent

from the following description and drawings, in which—

5 Fig. 1 is a front view of a section of wall constructed in accordance with my invention and showing the outer cement surface partly cut away to disclose the underlying structure and mounting of the cell members.

Fig. 2 is a bottom view of the section of wall shown in Fig. 1.

10 Fig. 3 is a perspective view of one of the cell members with its lining.

Referring more particularly to the drawing:

15 The cell members each comprises a piece of coarse mesh wire screening 10, or other reticulated material of required rigidity. A lining 11 of paper, thin fabric or fiber is glued to a sheet of the wire mesh material and the composite sheet is thereafter stamped to form 20 an inturned circumferential flange 12, the lining 11 being innermost. The cells so made can be packed and shipped without danger of breakage in transit between the places of manufacture and use. Also because of their 25 relatively flat, dish-like shape the cells may be packed for shipment in a minimum space, and the resulting small package is easily transported and handled.

30 While the cell members 10 are preferably of circular shape they may be of any other suitable or desirable shape such as for example, hexagonal, octagonal or the like, with equally good results.

35 The pre-formed cell members are anchored to the unfinished wall surface 13 by nails 14 or other suitable fastening means and are thereafter covered with a finishing coat of cement 15. Although ordinary plaster or cement may be used as a finishing coating, I 40 prefer to cover the cell members with a surface of so-called acoustic plaster which is composed of a mixture of plaster, cement or the like, and a filler, such for example as sawdust, asbestos, etc., adapted to aid in producing the desired resonance.

45 This cementitious outer coating fills in the spaces between adjacent cells 10 thereby assisting the nails 14 in securely anchoring them to the wall surface 13, and at the same 50 time forming an interlock with the projecting mesh of the wire cells and completely covering the cells to present a finished and unbroken wall surface 15.

What I claim is:

55 1. A cell for acoustic walls consisting of coarse wire mesh material formed with a flange for spacing it from the surface to which it is affixed in use, and a lining for said cell.

60 2. A cell for acoustic walls consisting of coarse wire mesh material formed with a flange for spacing it from the surface to which it is affixed in use, and a paper lining adhesively connected to said cell.

65 3. A wire mesh cell for acoustic cement

walls consisting of a skeleton wire cell, and a lining of paper, fiber or thin fabric glued or cemented to the wire cell.

4. A cell for acoustic walls comprising a skeleton frame formed with large interstices and a material applied to said frame to close the interstices and prevent the passage of plaster therethrough when the cell, affixed to a wall, is covered with plaster to render the wall resonant.

70 In testimony whereof I affix my signature. 75
EMILE BERLINER.
